UNITED STATES PATENT OFFICE.

JOHN S. BAKER, OF LOS ANGELES, CALIFORNIA, ASSIGNOR, BY MESNE ASSIGNMENTS, TO ANDERSON-BARNGROVER MFG. CO., OF SAN JOSE, CALIFORNIA, A CORPORATION OF CALIFORNIA.

COOKING APPARATUS.

1,315,076.

Specification of Letters Patent. Patented Sept. 2, 1919.

Application filed September 15, 1916. Serial No. 120,300.

To all whom it may concern:

Be it known that I, JOHN S. BAKER, a citizen of the United States, residing at Los Angeles, in the county of Los Angeles and State of California, have invented certain new and useful Improvements in Cooking Apparatus; and I hereby declare that the following is a full, clear, and exact description thereof, reference being had to the accompanying drawings, which form part of this specification.

This invention is a novel improvement in cookers of the type shown in Baker Patents #1,181,057 of April 25, 1916, and #1,182,832 of May 9, 1916, and the main object of the present invention is to enable two or more series of cans each of different size, and requiring different lengths of time for cooking, to be simultaneously passed through the machine and cooked.

Minor objects of the invention are to provide novel means for varying the thickness of the canways, especially at the bends thereof, also on bottom by raising and lowering plate upon which cans roll, so that they can be adjusted to suit different sizes of cans and properly direct same around the bends, also along bottom; to provide a novel construction of the canway; to provide novel means for discharging or directing cans out of the machine; and to provide novel means for discharging cans from either end of the machine at one or more points, thus increasing the flexibility of the machine for cooking all sizes of cans for different lengths of time without altering the speed or travel of the cans, and to prevent jamming of cans that may be passed through machine endwise thereby fortifying against shut downs, etc., in factory.

I will explain the invention with reference to the accompanying drawings which illustrate a cooker embodying my improvements, and a description thereof will enable others skilled in the art to fully comprehend the invention and adopt and use same in other forms or types of cookers within the scope of the claims defining the invention and following the description of the machine illustrated in said drawings:

In such drawings:

Figure 1 is a top plan view partly broken away and partly in section of a cooker embodying the invention.

Fig. 2 is an enlarged longitudinal sectional elevation through the right hand end of the machine on the line 2—2 Fig. 1.

Fig. 3 is a similar view on the line 3—3, Fig. 1.

Fig. 4 is a detail sectional view showing the end guards in Fig. 3 partly in section.

Fig. 5 is a section on the line 5—5, Fig. 4.

Fig. 6 is an enlarged plan view of one of the discharge runways showing one of the can throw-off devices.

Fig. 7 is a view similar to Fig. 6 showing the throw-off lever in initial position.

Fig. 8 is a detail view of another form of can throw-off.

Fig. 9 is a sectional view through one of the can inlets on the line 9—9, Fig. 10.

Fig. 10 is a sectional view on the line 10—10 Fig. 9.

Fig. 11 is a detail of the filler plates.

The tank or cooking chamber 1 may be of any suitable construction, and is shown as provided with removable covers 1^a, which may be provided with water-seals indicated at 1^b.

Within this tank is a perforated bottom plate 2 which may be raised or lowered to accommodate different size cans and prevent same from turning endwise in canway where water is used, etc.

Within the tank above the plate 2 is a preferably elongated spiral canway formed of metal T-bars 2^a attached to transverse supporting bars 2^b mounted on legs 2^c by which the canway is properly supported within the tank. The T-bars 2^a are preferably arranged with the leg or shank of the T outermost and the flange or head of the T innermost, and the bars are so arranged that the space between adjacent bars is wide enough to support a can upon the base flanges of the adjacent bars, while the shanks of the adjacent bars form guides to keep the cans in the canway, see Fig. 2.

At the top of the canway the cans are supported on the flanges of the bar, but at the bottom of the canway they are supported upon the perforated plate 2 but are guided by the shanks of the bars; and at the curved ends of the spiral canways the cans are guided by the legs or shanks of the bars, but they have to be supported by auxiliary means; which as shown in the drawings preferably consist of curved plates 3 arranged

at each end of the canway. Each plate 3 is preferably hinged at its bottom, in line with the end of the perforated plate 2 in a suitable manner, preferably upon a transverse rod or shaft 3^a suitably supported in the tank; and the upper end of each plate 3 is adjustable toward or from the bars 2^a so that the space between the inner face of this curved plate and the base of the said bars 10 can be varied by swinging the upper end of the plate inward or outward.

As shown each plate 3 may be adjusted preferably by means of two bars 3^c pivoted at their inner ends to the ends of plates 3 and 15 extending through slots 1^c in the adjacent end of the tank; and the bars 3^c may be notched as at 3^d, 3^e, and such notches can be engaged with the slots so as to hold the plate in the desired position. When the plates are ad- 20 justed so the innermost notches 3^d engage the slots, the plates will be adjusted to guide larger sized cans around the canway; and when the bars are adjusted so that the outer notches 3^e engage the edges of the 25 slots, the plate 3 will be adjusted so as to guide cans of smaller diameter around the canway. While I have shown but two notches in the bars additional notches may be provided to enable the plates to be ad- 30 justed to meet other sizes of cans.

It will be seen by reference to Figs. 1 and 4 I have arranged two plates 3 at each end of the canway, and this would enable me to run simultaneously through the machine two 35 sets of cans or more according to division of plate, of different size. It is necessary in order to enable cans to properly pass around the bends of the canway without binding that they should be properly guided therein 40 and this is accomplished by adjusting the plates 3 to suit the diameters of the cans being used; as the plates 3 are independently adjustable, either plate can be adjusted to suit larger or smaller cans; and thus for example 45 in the machine shown large cans can be run through either the right or left hand side of the machine, while smaller cans can be simultaneously run through at the other side of the machine. But if only one size can is 50 to be cooked the plates can be adjusted to suit either large or small cans. Of course in large machines more plates 3 may be employed at each end of the machine, to enable more than two different sizes of cans to be 55 run simultaneously through the machine if desired.

It will be observed that these plates 3 form the outer walls of the canways at the bents thereof; and for the purpose of dis- 60 charging the cans from the machine an opening or openings 3¹ may be made in the plates opposite the runs of canway; preferably the lower edge of each opening 3¹ is below the center line of the axis or curve of the axis 65 or curve of the end of the canway. The cans

would ordinarily pass out through this opening when they reach it, but this may be prevented by means of suitable devices; I preferably employ sliding gates to permit the escape of cans from the canway and as 70 shown a slidable gate 4 is attached to each plate adjacent each opening 3¹ therein such plates being guided in suitable retainers 3^f on the plates, and may be operated by means of levers 4^a pivoted on studs 4^b attached to 75 the end of the casing and entering the latter through slots therein and connected by links 4^c to the doors 4, as indicated in Figs. 2 and 3.

Said levers 4^a preferably extend out of the 80 tank and may be readily manipulated by the operator so as to open or close any opening in any plate. By this means cans can be discharged from any one of the canways through is related opening 3¹ by opening the 85 slide 4 controlling that run of the canway or may be retained in such run of the canway and caused to pass such opening if the slide is closed. In the normal position as shown in Figs 2 and 3 these slides 4 close the 90 openings and prevent the can from escaping from the runway.

When any slide is open the cans when they reach the opening uncovered by the slide will pass out of such opening onto a chute 5 by 95 in which they are directed to an opening 1^b in the adjacent end of the tank and which opening may be closed by a series of plates 6 and after passing through such opening the cans may be directed into either runway 7 100 or 8. By providing openings at each end of the machine the cans can be discharged from either end thereof and preferably when running two different sizes of cans simultaneously it is desirable to discharge different 105 cans at opposite ends of the machine, if only two different cooks are being used. This will facilitate handling of the cans.

Fillers 2^a may be placed between the guides of canways as shown in Fig. 1 to 110 guide cans that may be turned endwise so that they will pass through the machine without becoming jammed, etc. All ends should be chamfered so the end of oncoming can will not catch but will slide over. 115

When running large size cans the plates 3 will be adjusted farthest away in the outermost position so that the largest cans may be passed around the curves at the ends of the canway; if smaller cans are to be treated 120 the curved plates 3 would be adjusted inwardly so that they would lie nearer to the runs of the canway to accommodate small size cans and prevent the latter jumping or passing too far out of or from under control of the pusher bars. The cans may be propelled around the canway by means of an endless propelling device or pusher comprising endless side chains 10 running over suitable sprockets 10^a mounted on shafts 10^b 130

at each end of the machine; said chains being connected by transversely disposed bars 10^e which extend across the series of canways and are adapted to propel cans along 5 the canway. One of the shafts 10^b may be driven by suitable mechanism as in my said patent so as to propel the pusher in an endless path.

The can may be fed into the runs of the 10 canway as described in my said patents, through a feed indicated at 11 which may be of any suitable construction. As shown these feeders are located at the right hand end of the machine, see Figs. 1 and 9, and 15 the feed chute 11^b is attached to the end of the plate and extends inwardly over the first run of the canway and is adapted to deliver cans thereinto as indicated in Fig. 9 so that cans will be taken by the pusher bars and 20 propelled along the canway and around the spirals thereof, the cans successively passing the openings in the plate 3 at the left hand end of the machine when such openings are closed by the slides 4 and also passing 25 the openings in the plate 3 at the right hand end of the machine when such openings are closed by the slides; but when these slides are open the cans will pass out of such openings onto the runways 7 or 8.

30 A plurality of feeds may be employed if desired and as shown in Fig. 1 I have indicated a second feed at 11^c which may be constructed like feed 11 and is shown as arranged to deliver cans onto the runway at one of the intermediate runs thereof. Of course more feeds may be applied to the machine if desired, and feeds can be arranged at both ends of the machine if desired; one feed being indicated in dotted 40 lines 11^x at the left hand end of the machine, in Fig. 1, the feed 11^x being like feeds 11 and 11^c. The feed chutes or castings 11^b are wide enough to accommodate large size cans; if it is intended to feed small cans, in order that the latter may be properly directed into the canway, removable filler plates 11^e may be placed within and against the sides of the chutes as indicated in Figs. 45 9 and 10 and may be retained therein in any proper manner. These filler plates will narrow the chutes so as to properly direct small size cans onto the runway. At the front end of the machine the drive shaft which drives the endless chain 10 over 50 sprockets 10^a is fixed but at rear end this shaft may be moved forward or back by take-up boxes to accommodate stretch in chain. This changes the radial axis to the curves at rear end.

60 At the ascending end of the runway Fig. 3 it is only necessary to adjust plate 3 inwardly to accommodate small size cans, but at the other end of the canway when the cans descend it is desirable not only to adjust plate 3, but also to provide means for

narrowing the path of the can, and for this purpose the base of the T-bars may be cut away to accommodate a curved plate 12, see Figs. 2 and 5, which plate is hinged at top on a rod 12^a or in other suitable manner 70 and is connected at bottom to the rods 12^c which are in turn connected to a crank 12^d on a shaft 12^b which extends out of the machine and is operable by means of a lever 12^f and hand rod 12^g by which the guard 75 plate 12 can be adjusted either in or out to narrow or widen the path of the cans at will.

Assuming that large cans are being fed to 11 and small cans at 11^c Fig. 1 the larger 80 cans can be taken out by raising any slide 4 at either end of the tank between the feed opening where the cans are fed at 11 to a point where they are fed at 11^c, and smaller cans may be taken out by opening any slide 85 4 at either end of the tank between the point where the cans are fed at 11^c and the final discharge or end of the canway. In this way two series of cans of different size may be simultaneously treated or two cans of 90 the same size can be treated for different lengths of time on different products, and if more than two feeds are employed a corresponding increase of series or number of cans can be simultaneously treated in the 95 machine. Of course the length of the canway and the length of each run of the canway and the total number of runs of the canway or tank will be varied according to the number of feeds to be used and the greatest extent of movement to be given to the cans and greatest variety of products to be run simultaneously.

100 If desired cans can be fed at 11 and can be made to travel through the entire length 105 of the canway, or through any portion or section of the canway desired, and different sizes of cans cooked for different periods of time can be discharged into separate runways at either end of the machine. One 110 series of cans for example may be discharged on the runway 7 or another series of cans may be discharged onto the runway 8 by using a removable or shiftable bridge piece 115 8^e as indicated in Figs. 2 and 3. The runways may be provided with chain belts which take cans endwise toward the side of the machine; at the end of each runway means may be provided for automatically discharging cans from said runway, as 120 shown in Fig. 6 a bell crank discharging lever 13 is employed, this lever being pivoted at its bend on a belt 13^a and one arm of this lever extends normally across the runway and the other extends longitudinally of the runway, and the latter arm is preferably bowed as at 13^b. As the cans are brought forward on the runway which is moved by the conveyer as indicated by the arrow the cans strike arm 13^b and owing 130

to the bend in this arm moves the latter to the position shown in Fig. 7, which position throws the arm 13 of the lever forward into the path of the can, but as the can 5 strikes arm 13 of this lever it rocks the latter on its pivot and the arm 13^b engages the side of the can and rolls the latter off the carrier as indicated in Fig. 6, the can being indicated in dotted lines at C in both 10 figures; the can being knocked off or kicked off sidewise so that it will readily roll down the chute 8^c to any suitable receiver.

It may happen that the rim of sanitary cans will catch in the cracks D between the 15 joints in the connecting links of the conveyer 14 so that they cannot easily be kicked off by the lever 13 into trough guide 8^c without binding or turning endwise so I provide a strip 15 at one side of the conveyer which 20 strip extends over the edge of the conveyer, as shown in Figs. 6-8, and is fastened securely to the trough at points 15^a. This strip will disengage the cans from the joints in the conveyer in which its rim may have 25 become lodged. The kick-off lever 13 is fastened to the runway trough by a thumb screw preferably and is pivoted so that when a can strikes it when in the position shown in Fig. 6 the arm 13^b will be thrown 30 backward into position indicated in Fig. 7, and as the can continues to move forward, being carried by the conveyer 14 it will engage the arm 13 and force it back and automatically move arm 13^b back to position 35 shown in Fig. 6, and in so doing it will engage can C and throw it forward "over center" and the can will roll by gravity down the guide trough or chute 8^c. To prevent arm 13^b being thrown forward so that its 40 point might engage the end of the can and interfere with its progress I provide arm 13^b with a slide 13^e which has a hooked end that prevents too far inward movement of arm 13^b by engaging a stop 13^f when the kick-off 45 lever is in the position shown in Fig. 6. It will be seen that this throw off device may be regulated to a nicety by use of a set screw or similar device at 13^g to adjust for different size large cans.

50 The trough 7 Figs. 1 and 8, is shown as provided with an adjustable kick-off guide 16 adapted to operate on different sizes of small cans. One end of this kick-off 16 is pivoted at 16^a to the side of the trough and the other 55 end of this kick-off is adjustably connected in any suitable manner to plate 16^c at the outer end of the trough. As shown this plate is provided with perforations adapted to be engaged by a thumb bolt or screw 16^d 60 attached to or engaging the end of the kick-off 16. As the cans come forward on the conveyer 14 they are deflected laterally on the conveyer 14 by contact with the inclined kick-off 16 until by the time they reach plate 65 16^c they are overbalanced and roll off the

edge of the conveyer 14 into the receiver 7^c in a rolling position. By adjusting the outer end of the kick-off 16 it can be adapted to throw off larger or smaller cans from the conveyer 14 as they are brought forward 70 thereon. A vertical plate 16^e is provided to guide cans past the break between the end of the plate 16^c and the chute 7^c. In order to insure the cans passing out of the machine through an opening at the ascending end of 75 the tank Fig. 2 where the cans ascend, trips 17 may be provided, see Figs. 2 and 5; these trips being suitably pivoted on rods 17^a attached to lugs on the back of the guard plate 12. These trips may be connected by rods 17^b 80 to bell crank levers 17^c pivoted on a suitable supporting bar 17^d; extending across the machine and each lever 17^c being also connected to a rod 17^e leading out of the machine beside the tank so that any one of the trips 85 17 can be adjusted to operative position at will. When any slide 4 adjacent the guard is open for the discharge of a can the corresponding trip 17 should be adjusted so that as the cans ascend the runs and come opposite the opening left by the slide they contact with the projecting trip and are tilted off the bar and drop by gravity out through the opening in the chute 5 and then into the runway 7 or 8 according to whether or not 90 the bridge 8^c is in adjusted position. At the other end of the machine shown in Fig. 3 where the cans descend in passing around the bends of the canway they would not fall out by gravity as soon as they came to the 95 opening, but lest a small can might hang upon the pusher bars as they descend and possibly be carried past the opening it is desirable to provide trip devices for insuring that the cans shall drop forward off the 100 bars and out of the opening. For this purpose I provide a series of trip levers 18 pivoted on a rod 18^a extending across the machine, each trip lever being connected at one 105 end by a link 18^b to one end of the bell crank lever 18^c pivoted on a support 18^d extending across the machine, the other end of the bell crank being connected to a rod 18^e which extends out through the side of the tank. Whenever any slide 4 at the left hand end of 110 the machine is open for discharge of a can the roll trip 18 could be manipulated so as to be projected into the path of the can so that as the cans descend they will come in contact with the lever 18 and be tilted forward and 115 off the pusher bar upon which they are then lying and drop out by gravity through the opening onto the discharge plate and then into the trough 7^x or 8^x as indicated in the drawing.

125 What I claim is:

1. In a cooking machine the combination of a chamber, a canway therein, means for moving cans along the canway, means for discharging cans from the canway at a 130

plurality of points, means for feeding cans to the canway, and means for varying the width of the canway at different but adjacent bends thereof to enable a plurality of 5 series of cans of different size to be simultaneously traversed through the machine.

2. In a cooking machine the combination of a chamber, a spiral canway therein, means for feeding cans to the canway, means for 10 adjusting the canway at the bends thereof to suit different sizes of cans, and means for discharging cans from the canway through said adjusting means.

3. In a cooking machine the combination of a chamber, a spiral canway therein, means for feeding cans to the canway at a 15 plurality of points, means for adjusting the canway at the bend thereof to suit different sizes of cans, said means having openings 20 for the escape of cans from the canway and means for preventing the passage of cans through the openings.

4. In a cooker the combination of a chamber having a discharge opening, a canway 25 therein having bends and openings in the bends, adjustable slides at the bends of the canway adapted in one position to retain cans in the canway, means for independently adjusting the slides to permit cans to 30 pass from the canway to the discharge opening in the chamber, and means for conducting cans passing from the canway to said opening.

5. In a cooking machine the combination of a cooking chamber having outlet openings, a canway therein having bends, a curved plate forming the outer wall of a 35 bend of the canway, openings in this plate, slides on said plate adapted to retain cans in 40 the canway in one position and permit cans to escape therefrom in another position past the openings, and means for directing cans escaping from the canway to the related outlet opening in the chamber.

45 6. In a cooker the combination of a chamber having outlet openings, a canway therein having bends, openings in the bends, adjustable slides at the bends of the canway adapted in one position to close said 50 openings and retain cans in the canway, means for independently adjusting the slides to permit cans to pass from the canway, means for conducting cans passing from the canway to the related outlet opening; and means adapted to project into the path of 55 the cans opposite an open slide to cause cans to pass out of said canway.

60 7. In a cooker the combination of a chamber, a spiral canway therein, a plurality of 65 curved plates arranged side by side opposite the bend of the canway and adapted to direct cans around the canway, and means for independently adjusting these plates to suit cans of different size in different runs of the canway.

8. In a cooker the combination of a chamber, a spiral canway therein, a plurality of curved plates opposite the bends of the canway and adapted to direct cans around the canway, and means for independently adjusting these plates to suit cans of different size, said plates being provided with openings for the passage of cans from the canway, and adjustable means for closing selected openings. 70

9. In a cooker the combination of a chamber, a spiral canway therein, a plurality of curved plates opposite the bends of the canway, means for independently adjusting 80 these plates to suit cans of different size, said plates being provided with openings for the passage of cans from the canway, and adjustable means for closing selected openings; with means adapted to project into the path of the cans and cause the cans to pass out of the canway through an uncovered opening. 85

10. In a cooker the combination of a chamber, a spiral canway therein, a plurality of curved plates arranged side by side and forming the outer walls of a bend of the canway and adapted to direct cans around the bend, and means for independently adjusting these plates to suit cans of different 95 size in different runs of the canway. 90

11. In a cooker the combination of a chamber, a spiral canway therein, a plurality of curved plates opposite a bend of the canway adapted to direct cans around the bend, and means for independently adjusting these plates to suit cans of different size, said plates being provided with openings for the passage of cans from the canway, and adjustable means for closing selected openings. 100 105

12. In a cooker the combination of a chamber, a spiral canway therein, a plurality of curved plates opposite a bend of the canway and adapted to direct cans around the bend, and means for independently adjusting 110 these plates to suit cans of different size, said plates being provided with openings for the passage of cans from the canway, means for closing selected openings; openings in the chamber adjacent the said plates, and 115 means for directing cans passing through the openings in said plates to the openings in the chamber.

13. In a cooker the combination of a canway having a bend, a curved adjustable plate at the inner side of said bend for varying the depth of the canway, said plate having slots and ejector devices adapted to be projected through the slots in said plate to direct cans out of the canway. 120

14. In a cooker the combination of a canway having a bend, a curved adjustable plate at the inner side of said bend for varying the depth of the canway, ejector devices adapted to direct cans out of the canway, 130

means for adjusting the plate, and means for adjusting the ejector devices independently of the plate.

15. In a cooker the combination of a canway having a bend, curved adjustable slotted plates at the inner side of said bend for varying the depth of the canway, ejector devices adjacent said plates adapted to be projected through the slots in the plates to direct cans out of the canway, means for adjusting the plates, and means for adjusting the ejector devices independently of the plates.

16. In a cooker, a canway composed of an inner spiral formed of T-bars having their bases innermost and their flanges or shanks outermost, the spaces between the shanks forming channels to guide the cans, and the bases of the adjacent T-bars at the upper side of the spiral forming supports for the cans, a bottom plate below the spiral supporting the cans on the lower runs of the canway, curved plates at the bends of the spiral for guiding the cans around the bends,

and a series of longitudinally disposed filler plates arranged between the adjacent T-bars at the upper side of the spiral to support misplaced cans.

17. In a cooker, a canway composed of an inner spiral formed of a series of T-bars having their bases innermost and their flanges or shanks outermost, the spaces between the shanks of the bars forming channels to guide the cans, and the bases of adjacent T-bars at the upper side of the spiral forming supports for the cans, a perforated bottom plate below the spiral supporting the cans in the lower runs of the canway, curved plates at the bends of the spiral guiding the cans around the bends, and a series of longitudinally disposed filler plates arranged between the adjacent T-bars at the upper side of the spiral to support misplaced cans, substantially as described.

In testimony that I claim the foregoing as my own, I affix my signature.

JOHN S. BAKER.
